J. F. STUCKERT

ADJUSTABLE ROOF STRUCTURE

Filed July 3, 1924

UNITED STATES PATENT OFFICE.

JOHN FRANKLIN STUCKERT, OF PHILADELPHIA, PENNSYLVANIA.

ADJUSTABLE ROOF STRUCTURE.

Application filed July 3, 1924. Serial No. 723,855.

To all whom it may concern:

Be it known that I, JOHN FRANKLIN STUCKERT, a citizen of the United States, residing in the city and county of Philadelphia, State of Pennsylvania, have invented a new and useful Adjustable Roof Structure, of which the following is a specification.

This invention, generally stated, relates to a building construction and more particularly the roof thereof in which a skylight may be employed. In work of this kind, as at present practiced, no adequate provision is made from an engineer's viewpoint for compensating for inequalities, or distortion of the roof parts upon which a skylight is to be positioned. As a result roof parts frequently must be built up or a proper level secured by employing wedges or the like which in addition to being unsatisfactory from an engineering standpoint, consumes valuable time and is generally unsatisfactory since seepage or leaks are invited. The leading object of the present invention is to overcome these disadvantageous features and provide an arrangement, combination and connection of parts whereby a mechanically efficient and ready adjustment of skylight parts with respect to a building may be effected to ensure water-tight joints. Other and further objects reside in the provision of general details of construction for attaining the results sought by said leading object. Other and further objects not at this time appearing will be hereinafter more particularly referred to.

The invention consists of the novel construction hereinafter described and finally claimed.

The nature, characteristic features and scope of the invention will be more fully understood from the following description taken in connection with the accompanying drawings forming part thereof, and in which:

Fig. 1, a view in longitudinal section of a skylight structure embodying the invention.

Fig. 2, is a view thereof in cross-section, and

Fig. 3, shows in longitudinal section an alternative form of construction.

For the purpose of illustrating my invention I have shown in the accompanying drawings two forms thereof which are at present preferred by me, since the same

have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring now to the drawings in detail and with more especial relation to Figs. 1 and 2, the reference numeral 1 designates curbing upon a roof or side or other part of a structure to which a skylight is to be attached. While for illustrative purpose the curbing has been shown as of concrete obviously other material may be employed. Spanning the curbs 1 is a gutter 2 which may be a channel beam as illustrated or other suitable member. The gutter 2 is secured to the curbing by means of metal angle straps 3, the ends of each being reversely bent so that one end of each is arranged beneath the gutter 2 and the opposite end of each is arranged beneath the curbs 1. When the straps are secured to place (in a manner to be presently described), the gutter is anchored to the curbing. Arranged above and spaced from the gutter 2 is the skylight support shown as being an inverted channel beam 4 upon which is positioned composition board, sheet asbestos, a plate of glass or the like 5. Upon said plate 5 is arranged another channel beam 6, said beams 2, 4 and 6 being arranged in parallelism. These beams at each end, including the plate of glass and the upper ends of straps 3, are apertured in register for the passage therethrough of bolts 7, or rods 7', screw threaded at each end. Nuts 8 upon said rods secures each strap 3 to the gutter 2 and nuts 9 upon said rods and nuts 9' upon said bolts clamps the plate of glass between the broad faces of the channel beams 4 and 6. Channel beam 4 is spaced from the gutter by means of thimbles 10 through which the bolts pass, lock nuts 11 being present upon said bolts and rods for interlocking the parts together. The skylight structure is finished with usual metal sheeting 12.

Referring now to Fig. 3, an alternative form of skylight structure is shown although the adjusting principle is the same. The gutter 13 in this instance rests upon the curbing 1 and is secured to the latter by an angle strap 14, one of the bolts 7 being used

in the connection. The glass 5 is clamped between members 15—16 by the nut 9' and lock nut 17 at one end and by means of nut 9 and a thimble 18 arranged between a channel iron 19 and plate 20 which rests upon the gutter 13 at the other end. Metal sheeting 21 is employed as shown.

In positioning a plate of glass 5 in a skylight structure as above described any inequalities or distortion of the curbing, gutter or supporting members 4 or 16 may be compensated for by adjusting the various nuts upon the bolts to obtain a desired position of the skylight proper with respect to the other parts thereof.

The present invention is an improvement upon the device shown in my U. S. Letters Patent No. 316,413 dated April 21, 1885. While I have shown and described for illustrative purposes a skylight construction I wish it distinctly understood that a roof or other construction is contemplated by the present invention. As an example the invention is applicable to rail-road car roofs. While I have shown and described glass as the element used for spanning the curbs or other supports, obviously, any material may be used and the bolts or threaded rods used for securing adjustment of parts are very well adapted for general application in any of these various structures. Putty or other material 22 may be used to cause adhering of beams 4—6 and glass plates 5 or the like.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

50 1. In a building construction a pair of supports, a gutter spanning said supports, means arranged above said gutter for supporting a roof in a fixed, rigid manner means for securing predetermined adjustments of said supporting means toward or

away from said gutter at the time of erection and means for retaining permanent said adjustments.

2. In a building construction a pair of supports, a gutter spanning said supports, means arranged above said gutter for supporting a roof in a fixed, rigid manner, sheets of roofing material arranged upon said supporting means, means for securing predetermined adjustments of said supporting means toward or away from said gutter at the time of erection and means for retaining permanent said adjustments.

3. In a building construction a pair of supports, a gutter spanning said supports, means arranged above said gutter for supporting a roof in a fixed, rigid manner, sheets of roofing material arranged upon said supporting means, means including bolts or rods arranged to secure predetermined adjustments of said supporting means including the roofing material toward or away from said gutter at the time of erection and means for retaining permanent said adjustments.

4. In a skylight structure a curbing, a gutter supported thereon, glass supporting means arranged above said gutter in fixed manner means including bolts or rods for adjusting said supporting means including said glass toward or away from said gutter at the time of erection and means for retaining permanent said adjustments.

5. In a skylight structure a curbing, a gutter supported thereon, glass supporting means arranged above said gutter in fixed manner means including bolts or rods at each of said gutter for adjusting said supporting means including said glass toward or away from said gutter at the time of erection and means for retaining permanent said adjustments.

6. In a skylight structure a curbing, a gutter supported thereon, glass supporting means arranged above said gutter in fixed manner, a bolt or rod at each end of said gutter provided with means for sustaining said glass supporting means in fixed manner, and nuts and lock nuts for said bolts or rods to secure permanent adjustment of said glass supporting means toward or away from said gutter at the time of erection.

In testimony whereof, I hereunto signed my name.

JOHN FRANKLIN STUCKERT.
